UNITED STATES PATENT OFFICE.

ELMER E. THOMAS, OF HARDIN, ILLINOIS.

GRINDING APPARATUS.

Application filed April 19, 1924. Serial No. 707,677.

To all whom it may concern:

Be it known that I, ELMER E. THOMAS, a citizen of the United States, residing at Hardin, in the county of Calhoun and State 5 of Illinois, have invented certain new and useful Improvements in Grinding Apparatus, of which the following is a specification, reference being had to the accompanying drawings.

10 This invention relates to certain improvements in grinding apparatus and has relation more particularly to a device of this general character especially designed and adapted for use in connection with the 15 grinding out of cylinders and kindred internal work and it is an object of the invention to provide a device of this kind having novel and improved means whereby the grinding or working element can be positioned or adjusted with respect to the work 20 as the requirements of practice may necessitate.

Furthermore it is an object of the invention to provide a device of this general 25 character comprising a drum adapted to be snugly engaged within the bore of a casting or the like to be ground, said drum having arranged therein a grinding element adapted to be suitably projected through an opening formed in a wall of the drum to engage 30 the surface to be operated upon together with means operable exteriorly of the drum for adjusting said grinding element as required.

35 The invention consists in the details of construction and in the combination and arrangement of the several parts of my improved grinding apparatus whereby certain important advantages are attained and the 40 device rendered simpler, less expensive and otherwise more convenient and advantageous for use, as will be hereinafter more fully set forth.

45 The novel features of my invention will hereinafter be definitely claimed.

In order that my invention may be the better understood, I will now proceed to describe the same with reference to the accompanying drawings, wherein:

50 Figure 1 is a view in elevation illustrating a grinding apparatus constructed in accordance with an embodiment of my invention;

Figure 2 is an enlarged fragmentary view in elevation of the means as herein disclosed for adjusting the grinding element toward or from its work and for moving said element along the work;

Figure 3 is a fragmentary view partly in section and partly in elevation illustrating 60 details of construction as comprised in Figure 2;

Figure 4 is an enlarged fragmentary vertical sectional view with parts in top plan of the drum and the parts immediately associated therewith;

Figure 5 is a view partly in section and partly in plan of the structure shown in Figure 4, the line of section being substantially at right angles to that of the line of 70 section in Figure 4;

Figure 6 is a sectional view taken substantially on the line 6—6 of Figure 4, looking in the direction of the arrow;

Figure 7 is an enlarged fragmentary view 75 partly in section and partly in elevation illustrating in detail the driving mediums for the apparatus as herein set forth;

Figure 8 is a view in end elevation of the structure as illustrated in Figure 7;

Figure 9 is a sectional view taken substantially on the line 9—9 of Figure 7;

Figure 10 is a sectional view taken substantially on the line 10—10 of Figure 7.

As disclosed in the accompanying drawings, 1 denotes a supporting member or base of desired configuration and which is provided at predetermined points spaced longitudinally thereof with the upstanding posts 2 and 3 provided at their tops with the bearings 4 and 5 respectively.

Rotatably supported by the bearing 4 is an elongated tubular member 6, said member 6 being free to rotate and also free to have lengthwise movement through the bearing 4. The inner end portion of the member 6 is received within a split collar 7 carried by the head 8 of the drum D, said collar 7 being adapted to be clamped to the member 6, in a well-known manner by a coacting nut and bolt as indicated at 9. By this means the inner end portion of the member 6 and the head 8 are effectively locked one to the other for unitary movement.

Clamped to the outer end portion of the 105 member 6 is a split sleeve 11 constituting a

- hub for the end wheel 12, the purpose of which being hereinafter more particularly referred to.
- 5 Rotatably supported by the bearing 5 is an elongated tubular member 14 also being freely movable longitudinally through said bearing and the inner end portion of the member 14 is clamped within the split collar 15 carried by the second head 16 of the drum D, said collar 15 being held in a conventional way in clamping engagement with the member 14 through the coacting bolt and nut 17 whereby the head 16 and the member 14 are united for unitary movement.
- 10 15 Each of the heads 8 and 16 partially telescope within the cylindrical wall 18 of the drum and is held in applied position through the medium of the threaded members 19, the outer end portions of which being flush with the peripheral face of the wall 18. The drum D is of a diameter to substantially snugly engage within the bore of the casting to be worked and the wall 18 at substantially its longitudinal center is provided 20 with an elongated opening 20 through which is adapted to be projected as desired the grinding element or disc 21. The disc 21 partially extends within the kerf 22 provided in the outer end portion of an arm 23, said disc being fixed to a shaft 24 rotatably supported by said arm 23. The opposite end portion of the arm 23 extends between two longitudinally spaced internal flanges 25 carried by the wall 18 and is supported 25 for pivotal movement by the pin 26 held by said flanges 25 and disposed through the arm 23. Disposed between the flanges 25 and the arm 23 are the retractile springs 27 which serve to move the arm 23 in a direction to urge the grinding element or disc 21 inwardly through the opening 20 away from the work yet permitting said element or disc 21 to have outward movement as the necessities of practice may necessitate.
- 30 35 40 45 50 55 60 65 70 75 80 85 90 95 100 105 110 115 120 125 130
- The opposite end portions of the member 14 have fixed therein the bushings 27' which provide mountings for the tubular shaft 28 extending through the member 14, the inner end portion of which being received within the opening 29 provided in the axial center of the head 16. The bore 30 of the shaft 28 is angular in cross section and fitted within the inner end portion of the bore 30 of said shaft 28 is a block 31 operatively connected with an end portion of the shaft 24 through the medium of the universal connection 32 whereby upon rotation of the shaft 28 desired rotary movement is imparted to the grinding element or disc 21.
- Extending upwardly from the base member 1 outwardly of the post 3 is a pedestal 33 provided at its upper end portion with the spaced bearings 34 providing a mounting for the sleeve 35 the bore 36 of which being angular in cross section. Mounted upon
- the sleeve 35 intermediate the bearings 34 is a pulley 37, said pulley being keyed, as at 38, or otherwise held to the sleeve 35 for unitary rotation therewith. The pulley 37 is adapted to be driven by a belt leading from a suitable source of power. Snugly fitting within the bore 36 of the sleeve 35 is an end portion of a shaft 39, the same being held against endwise movement with respect to the sleeve 35 by the binding screw 40 or the like. The shaft 39 is of desired length and is telescopically engaged within the bore 30 of the shaft 28 hereinbefore referred to whereby said shaft 28 is driven from the shaft 39 yet permitting the shaft 28 to be moved lengthwise relative to the shaft 39.
- Engaged within the opposite end portions of the member 6 are the bushings 41 providing bearings for the shaft 42 extending through the member 6 and within the drum D through a central opening 43 provided in the head 8. The inserted end portion of the shaft 42 is provided with a crank arm 44 of desired length but provided at its free end portion with a lateral extension or pin 45 overlying the arm 23 and contacting therewith. Upon requisite rocking movement being imparted to the shaft 42 the grinding element or disc 21 may be projected or retracted with respect to the periphery of the drum D as the requirements of practice may desire.
- The outer end portion of the shaft 42 extends beyond the outer end of the member 6 and fixed to said outer end portion is a rock arm 46 having its outer end portion bifurcated. Fitting within the kerf 47 provided by such bifurcation is a block 48 supported for swinging movement by the pin 49 disposed through the block 48 and the arm 46. Threaded through the block 48 is shank 50 of desired length, the outer end portion of which being freely disposed through a sleeve 51 and provided beyond the sleeve 51 with an operating wheel 52. The shank 50 is held against lengthwise movement with respect to the sleeve 51 through the medium of the nuts 53 engaged with said shank adjacent the opposite ends of the sleeve 51. The sleeve 51 has a swivel connection 54, as indicated by broken lines in Figure 2, with a spoke 55 comprised in the wheel structure 12. By requisite turning of the shank 50 through the medium of the wheel 52, the arm 46 will be rocked as desired to effect the requisite projection or retraction of the grinding element or disc 21.
- In practice, the casting to be internally ground is suitably supported within a holder generally indicated at H in Figure 1, said holder being preferably of a character whereby the casting may be properly adjusted to effect the desired centering. The holding means H forms no particular part

of the present invention and it is believed that a detailed illustration and description thereof is unnecessary.

Before the casting is applied to the holder H, the head 8 is disconnected from the wall 18 and the member 6 moved outwardly a distance sufficient to position said head 8 beyond the outer end of the holder H. It being also understood that the member 14 10 has been moved outwardly sufficient to position the drum D beyond the opposite end of the holder H, as illustrated in Figure 1. After the casting has been applied to the holder H the head 8 together with the member 6 may be moved inwardly and through the bore of the casting after which said head 8 is again operatively connected with the drum D. The member 6 and drum D are then moved in a direction to engage the drum 20 D within the bore of the casting and after properly arranged therein, the wheel 52 is operated to bring the element or disc 21 into proper contact with the wall of the bore of the casting. The shaft 28 is then 25 rotated through the instrumentality of the shaft 39 to effect the desired operation of the element or disc 21. By imposing proper stress or strain upon the member 6 preferably through the medium of the wheel 12, the element or disc 21 30 may be caused to operate upon the wall of the bore of the casting at any point therealong and by rotating the member 6, also through the medium of the wheel 12, the element or disc 21 35 may be brought into contact with the wall of the bore of the casting at any point therearound. It is also to be particularly noted that the desired adjustment of the element or disc 21 through the medium of the shaft 40 42 may be effected during the period said element or disc is in rotation.

From the foregoing description it is thought to be obvious that a grinding apparatus constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:-

1. An apparatus of the class described comprising a drum, provided with heads, one of said heads being removable, said drum being provided in its peripheral wall with an opening, tubular members supported for endwise movement, and rotatable movement, means for securing each of said members and a head of the drum, a grinding

element rotatably supported within the drum and supported for movement with respect to the peripheral wall of the drum, means extending through one of the tubular members for regulating such movement of the grinding element with respect to the peripheral wall of the drum, and means disposed through the second tubular member and coacting with the grinding element for rotat- 70 ing the same. 75

2. An apparatus of the class described comprising a drum provided with an opening in a wall thereof, tubular members engaged with the opposite ends of the drum, means coacting with said members for supporting the same for both rotary movement and endwise movement, a grinding element within the drum and adapted to project through the opening in the wall of the drum, means extending through one of the tubular members and operatively engaged with the grinding element for rotating the same, means engaged with the second tubular member for manually rotating the drum, and means extending through the second tubular member and coacting with the grinding element to effect a projection or retraction thereof with respect to the peripheral wall of the drum. 80 85 90

3. An apparatus of the class described comprising a drum provided with an opening in a wall thereof, an arm mounted within the drum for swinging movement, a grinding disc rotatably supported by the arm and adapted to project through the opening in the drum, a tubular member connected to the drum, a rod disposed through said tubular member and extending within the drum, the inserted end portion of the rod having a rock arm coacting with the swinging arm carrying the grinding disc to impart swinging movement to said first named arm, and means for rotating the rod. 95 100 105

4. An apparatus of the class described comprising a drum provided with an opening in a wall thereof, an arm mounted within the drum for swinging movement, a grinding disc rotatably supported by the arm and adapted to project through the opening in the drum, a tubular member connected to the drum, a rod disposed through said tubular member and extending within the drum, the inserted end portion of the rod having a rock arm coacting with the swinging arm carrying the grinding disc to impart swinging movement to the said first named arm, and means carried by the tubular member for rotating the rod. 110 115 120

5. An apparatus of the class described comprising a drum provided with an opening in a wall thereof, an arm mounted within the drum for swinging movement, a grinding disc rotatably supported by the arm and adapted to project through the opening in the drum, a tubular member connected to 125 130

the drum, a rod disposed through said tubular member and extending within the drum, the inserted end portion of the rod having a rock arm coacting with the swinging arm carrying the grinding disc to impart swinging movement to said first named arm, a rock arm carried by the outer end portion

of the rod, and means coacting with said rock arm to impart rocking movement to the rod.

In testimony whereof I hereunto affix my signature.

ELMER E. THOMAS.
